Specification of Letters Patent. Patented Aug. 18, 1914.

Application filed February 16, 1912. Serial No. 677,978.

To all whom it may concern:

Be it known that we, ARTHUR H. ADAMS and AMOS F. DIXON, citizens of the United States, residing at Sparkill, in the county of Rockland and State of New York, and at Newark, in the county of Essex and State of New Jersey, respectively, have invented a certain new and useful Improvement in Telegraph Systems, of which the following is a full, clear, concise, and exact description.

This invention relates to printing telegraphs and has for its principal object to provide an improved controlling system for mechanical printers whereby high speed, accurate operation and a simplification of the controlling apparatus may be obtained.

Another object of our invention is to provide a controlling system for mechanical printers of a simplified nature and arrangement in which the controlling impulses from a distant station are transmitted over but two conductors.

In the drawings Figures 1 and 2 combined illustrate diagrammatically a receiving system embodying the invention with so much of the mechanical details of the apparatus as are necessary to understand the working of the system illustrated on Fig. 2 in perspective.

30 A sufficient description of the circuits and apparatus will appear from a detail description of the operation of the system.

Let it be assumed that the operator at the distant station desires to print a letter or character on the receiving apparatus shown in Figs. 1 and 2. Let it be specifically assumed that she desires to print on the recording medium the letter I, and that the combination of impulses that will selectively operate and print the letter I is negative impulse over line L_1 and a positive impulse over line L_2 , the two impulses being separated by an interval of no current. The negative impulse arriving over the line conductor L_1 , passes through the neutral relay 66, the polarized relays 1, 2 and 6 to ground and back to battery. Relays 66, 2 and 6 attract their armatures closing a circuit which may be traced from battery 100 through the string relay 2', winding of relay 42, armature of polar relay 2, armature 72 of the cut-out relay 103, winding of relay 41, armature of neutral relay 67, conductor 141, armature 77 of the cut-out relay 104, conductor 101,

contact spring 102 of the starting relay 109, to ground, and back to battery. As a result of the closure of this circuit, the string relay 2' is operated forming a path for current, from the battery 100, through the winding and armature thereof, windings of the relays 21, 23, 24, 25 and 26 in series in the order named, cut-out relay 103, cut-out relay 104, conductor 105, back contact and armature 106 of the clearing-out relay 107, to ground. The cut-out relays 103 and 104 do not operate at this time because of the following low resistance shunt circuit: conductor adjacent to the winding of 2', through the winding of relay 42, armature of relay 2, armature 72 of cut-out relay 103, winding of relay 41, armature of neutral relay 67, conductor 141, armature 77 of cut-out relay 104, conductor 101, contact spring 102 of the starting relay 109, to ground and back to battery. The first impulse is now at an end and owing to the fact that no current flows through the locking winding of the polar relay 2, the armature thereof falls off at the end of the impulse and opens the above traced shunt circuit around the relays 21, 23, 24, 25 and 26, thus allowing an increase of current to flow from the battery 100, through the string relay 2', and armature thereof, relays 21, 23, 24, 25 and 26 in series in the order named, cut-out relay 103, cut-out relay 104, conductor 105, armature 106 to ground and back to battery, retaining the string relay 2' in locked condition and operating the cut-out relays 103 and 104, which relays attract their armatures 71 to 74 and 75 to 77 inclusive. At the beginning of the second impulse of the combination which in the case of the letter I, was assumed, to be a positive impulse arriving over line conductor L_2 , the impulse passes through the neutral relay 67, the polar relays 5, 4 and 3 to ground and back to battery energizing the relays 6, 7, 5 and 3, closing the circuit which may be traced from battery 100 through the winding of string relay 3', winding of relay 43, and, because of the short circuit through the armature 73 of the cut-out relay 103 being opened, the circuit passes through locking winding of the polar relay 3, through the string of windings 13, 23, 53 and 63, through the armature of the neutral relay 66, conductor 141, conductor 108, energizing winding of the starting relay 109, to ground and

back to battery. It will be noted that current is now flowing through the string of windings 21, 23, 24, 25 and 26, and also through the string of windings 13, 23, 53 and 5 63, resulting in the energization of the relay 23 and the attraction of its armature 117 (shown in Fig. 2). The closure of this circuit also operates the starter relay 109 which attracts its armatures 110 and 111. The attraction of armature 110 closes a circuit which may be traced from battery 112, armature 110, conductor 113, starting magnet 114, to ground and back to battery. The starting magnet 114 is, therefore, energized, 10 attracting its armature removing the pawl at the outer end thereof from engagement with the ratchet 190 fast on the type-shaft 115, allowing the type-shaft to revolve in an anti-clockwise direction. The shaft 115 revolves under the influence of the spring 116 and is brought to rest by the radial arm 119 coming into engagement with the uplifted end of the armature 117 of the selected type magnet, and with the character I on the 15 type-wheel 191 in printing position. Radial arm 119 contacting with the armature 117 completes a circuit for the clearing-out relay 107, which may be traced from battery 118, radial arm 119, armature 117, conductor 120, 20 energizing winding of the clearing-out relay 107, to ground and back to battery. The clearing-out relay 107 attracts its armatures 106, and 127. In the meantime the starting relay 109, by the attraction of its armatures, 25 has closed a circuit which may be traced from battery 126, armature 125 of the reset relay 41, conductor 124, spacing magnet 122, armature 111 and contact spring 102, to ground and back to battery, causing the 30 energization of the spacing magnet 122 and the moving forward of the paper carriage through the space of one letter or character, thus providing a clean surface on which to print the same. The attraction of the armature 106 causes the opening of the selecting circuit, with the exception of what may possibly flow from the battery 100, string relay 3', relay 43, locking winding of polar relay 3, the windings of the relays 13, 23, 53 and 35 63, armature and back contact of the neutral relay 66, conductor 141, conductor 108, starting relay 109, to ground and back to battery, provided the line impulse is not ended and the polar relay 3 is held operated by the circuit through its operating winding. On the 40 opening of the circuit through the cut-out relays 103 and 104, the armatures 71 to 77 inclusive return to their normal or retracted position, short-circuiting the locking winding of the polar relay 3, relays 13, 23, 53 and 63, but does not short-circuit the starting relay 109 because of the open contact existing between contact spring 102 and conductor 101. Upon the cessation of the second impulse provided the clearing-out relay 45

107 has operated, the front contact of the polar relay 3 will open, breaking the circuit existing through the starting relay 109, causing the armatures thereof to return to their normal position. However, before the starting relay 109 is deenergized a circuit is closed which may be traced from battery 112, armature 110, conductor 113, printing magnet 121, conductor 129, armature 127 and contact spring 128, of the clearing-out relay 107, to ground and back to battery. The closing of this circuit causes the printing magnet 121 to attract its armature and the printing operation now takes place, and when the starter relay is deenergized its armatures return to their retracted position, and a circuit is closed which may be traced from battery 112, armature 110, conductor 133, retractor magnet 132, conductor 131, armature 106, to ground and back to battery. The retractor magnet 132 through its armature rotates the shaft 115 in a clockwise direction a sufficient distance to break the circuit closed between the radial arm 119 and the armature 117. The breaking of this circuit causes the deenergization of the clearing-out relay 107, which allows its armatures to fall back, breaking the circuit through the retractor magnet, and all parts of the device return to normal. 95

It will be noted by reference to Fig. 2 that the type-wheel 191 has two rows of characters thereon, and that printing is ordinarily done from the upper row of characters. If it is desired to print any of the characters shown on the lower row of the type-wheel a combination of impulses is sent from the distant station to energize the shift magnet 138, which attracts its armature, and the outer end thereof contacting with the underface of the type-wheel moves the type-wheel longitudinally of the type-shaft 115 bringing the lower row of characters into printing position. Let it be assumed that the combination of impulses necessary to select and operate the shift magnet 138 is composed of two impulses, the first negative over line L_2 , the second positive over lines L_1 and L_2 , the two impulses being separated by an interval of no current. The first impulse of the combination energizes the relay 67 and the polar relay 4, closing a circuit from battery 100, string relay 4', armature of polar relay 4, armature 74 of the cut-out relay 103, armature of the neutral relay 66, conductor 141, armature 77, conductor 101, contact spring 102 of the starting relay 109, to ground and back to battery. The closure of this circuit operates the string relay 4', which attracts its armature, closing a circuit which may be traced from battery 100, lower winding and armature of the string relay 4', conductor 139, through the windings of the relays 45, 46, 43, 41 and 42, in series in the order 110 115 120 125 130

named, conductor 140, contact spring 123 of the clearing-out relay 107, to ground and back to battery. Only a very small amount of current flows through the circuit just traced due to the shunt circuit, as was described in the case of type-magnet selection. At the end of the first impulse the contact and armature on the polar relay 4 are separated, thereby increasing the current through the above traced path, bringing the current in the relays 45, 46, 42, 41 and 42, to about one-half the operating value. The second impulse of the combination is now sent from the distant station, and operates the neutral relays 66 and 67 and the polar relays 1, 3 and 5. It will be noted that when the string relay 4' is operated, a circuit was closed through the cut-out relays 101 and 104, and that, therefore, these relays are not operated on the second impulse as is the case with the type selection. The operation of the polar relay 5 closes a circuit which may be traced from battery 108, conductor 140, string relay 5', relay 45, armature 142, conductor 141, armature 77, conductor 106, contact spring 102, to ground. It also closes a path from armature 77, conductor 106, starting relay 109, to ground. The starting relay 109 does not operate at this time, however, because of the short-circuit existing from armature 77 of the cut-out relay 104, conductor 101, armature 102, to ground. The circuit just traced operates the string relay 5', and in conjunction with the circuit locked up by the first impulse, operates the relay 45, which attracts both its armatures 142 and 143. A path is also closed by the armature of the string relay 5', which may be traced through the windings 51 and 52 to 56 inclusive, cut-out relays 103 and 104, conductor 105, armature 100, to ground, but an operating current does not flow through the relays 51, 52 to 56 inclusive owing to the low resistance shunt existing through relay 45. The attraction of the armature 142 closes a circuit from battery 114, armature 142, conductor 148, operating winding 146, to ground. Relay 146 attracts its armature 147, but the shift does not operate at this time owing to the short-circuit existing from battery 114, through armature 112, conductor 113, to the point outside the operating winding of 146. A circuit is also closed by the operation of relay 45, which may be traced from battery 114, armature 143, conductor 148, conductor 129, clearing-out relay 107, to ground and back to battery. This last named circuit operates the clearing-out relay 107, which opens at the contact spring 128 a circuit from the conductor 110, through the relays 45, 46, 42, 41 and 42. At the cessation of the second impulse current is taken off the remaining

winding of relay 45 by the deenergization of the polar relay 5, allowing the selecting circuit to go back to normal. The armatures 141 and 143 are retracted and armature 142 removes the short-circuit from about the shift magnet 138, causing current to flow from battery 126, armature 125, conductor 151, armature 150, conductor 149, shift magnet 138, conductor 103, armature 147, energizing winding of the relay 146 to ground and back to battery. Shift magnet 138 is energized attracting its armature, and the outer end thereof contacting with the underside of the type-wheel 191, moves the same longitudinally of the shaft, bringing the characters on the lower row into printing position, the circuit for the shift magnet being locked as above described. All printing will now take place from the characters on the lower row of type until the end of the line is reached, or until the unshift relay 46 is selected and operated. The combination of impulses, which will operate the unshift relay 46, is composed of a negative impulse over lines L_1 and L_2 , the two impulses being separated by the usual interval of no current.

It may be noted that the combination of impulses that will energize the unshift relay 46 is the same combination of impulses that will select and energize the Z type-magnet. This combination of impulses has, therefore, a distinct function, and the circuit is so arranged that if the type-wheel is in its normal position, that is, with the shift magnet not energized, the combination of impulses just described will select and operate the Z type magnet, but if the type-wheel is shifted by the energization of the shift magnet 138 the combination of impulses just described will select and operate the unshift relay 46.

When the shift magnet 138 is energized and locked, the first impulse of the combination of impulses just described will leave the selecting circuit in exactly the same condition as described for the first impulse of the shift combination. The second impulse which is negative arriving over lines L_1 and L_2 , operates the polar relays 2, 4 and 6 and the neutral relays 66 and 67. This impulse will select and close a circuit through the shift relay 46, which relay attracts its armature 150, breaking the locking circuit of the shift lock relay 126 and the shift magnet 138. The shift magnet being deenergized allows its armature to retract and the type-wheel 191 returns to its normal position. The unshift relay 46 when it attracts its armature 150 closes a circuit which may be traced from battery 126, armature 125, conductor 151, armature 150, conductor 152, conductor 103, contact 154, conductor 120, energizing-out relay 107, to ground and back to battery. The clearing-out relay 107 is en-

ergized attracting its armature and removing ground from the selecting circuit above traced allowing all parts of the device to return to normal. There is a winding 155 on the shift lock relay 146 which acts as a locking winding, preventing the falling back of the armature 158 as long as any current flows through string relay 6', thereby preventing the operation of the Z type magnet 10 in case the second impulse of a combination is a long one.

To provide for spacing between successive words a relay 43 is provided which when selected and operated closes an energizing circuit for the spacing magnet 122, but as the selection and operation of this relay is precisely analogous to that of the shift and unshift relay a detail description is considered unnecessary. It is only necessary to note that an impedance 159 is provided in the circuit to the clearing-out relay 107 to delay the operation of the clearing-out relay until after the spacing operation is completed.

To reset the paper carriage alone, the reset relay 41 is selected and energized, which closes a circuit for the reset magnet 135. To reset the paper carriage from any point in its stroke, and when the paper carriage reaches its normal or initial position to lift the paper to provide a clean surface for the next succeeding line of characters, a combination of impulses is sent from the distant station to select and operate the reset and paragraph relay 42. The first impulse of this combination operates the polar relay 4, which operating leaves the selecting circuit in the same condition as the first impulse of the shifting operation. The second impulse operates the polar relay 2, which closes a circuit from battery 100, string relay 2', winding of relay 42, armature of the polar relay 2, armature 72 of the cut-out relay 163, winding of relay 41, armature of the neutral relay 67, conductor 141, armature 77, conductor 101, contact spring 102, to ground and back to battery. It is to be noted that the selecting circuit passes through the energizing windings of both the relays 41 and 42, and both are energized attracting their armatures 125 and 104, respectively. The attraction of the armature 125 of the reset relay 41 closes a circuit which may be traced from battery 126, armature 125, conductor 162, conductor 163, reset magnet 135, to ground and back to battery. The closure of this circuit energizes the reset magnet 135, which attracts its armature removing the pawl at the outer end thereof from engagement with the ratchet and allowing the paper carriage to return to its normal or initial position. When the carriage reaches its normal or initial position the pin 197 contacting with the pin 198 on the slideable bar 199, moves the insulating pin 200 into engagement with the contact plate 166, bring-

ing all the contact plates 166 to 169 inclusive into engagement with each other, and closing a circuit for the paper lift magnet 136, which may be traced from battery 126, armature 125, conductor 162, armature 164, conductor 172, paper-lift magnet 136, conductor 171, contact plates 169 and 168, to ground and back to battery. The closure of this circuit energizes the paper-lift magnet 136, which attracts its armature, moving the end of the arm 201 into cooperation with the pivoted stop 202, gripping the paper therebetween, and moving the same upwardly a sufficient distance to insure a clean surface for the succeeding line of characters. The attraction of the armature of the paper-lift magnet 136 causes the engagement of the contact plates 173 and 174, closing a circuit for the clearing-out relay 107, which may be traced from battery 175, contact plates 173 and 174, conductor 176, conductor 178, conductor 160, conductor 148, conductor 120, energizing winding of the clearing-out relay 107, to ground and back to battery. The closure of this circuit energizes the clearing-out relay 107, which attracts its armatures removing ground from the selecting circuit above traced, and allowing all parts of the device to return to normal position.

While we have shown on the drawings a plurality of batteries or sources of current, it will be understood that where such batteries or sources of current are of the same character or potential and located at the same place, they may be and preferably are one and the same battery or source of current.

What we claim is:

1. In a printing telegraph the combination with a rotatable type shaft carrying a type-wheel having two rows of characters thereon, either row of which may be presented for printing therefrom, of electromagnetic means for presenting either row of type to printing position and locking the same in such position, an operating circuit for said electromagnetic means, and means for closing said operating circuit comprising a selecting circuit having two branches and selected by a combination of two impulses.

2. In a printing telegraph the combination with a rotatable type shaft carrying a type-wheel having two rows of characters thereon and movable longitudinally of the shaft, of electromagnetic means for moving said type-wheel longitudinally of the shaft and locking the same in operated position, an operating circuit for said electromagnetic means, and means for closing said operating circuit comprising a selecting circuit having two branches and selected by a combination of two impulses.

3. In a printing telegraph the combination of a rotatable type-wheel having two

- rows of characters thereon, one of the rows being the one from which the printing is ordinarily done, means for moving the type-wheel longitudinally of its axis to bring the 5 other row of characters into printing position and locking the same in operated position, a selecting circuit for selectively energizing the operating means comprising a plurality of branch circuits and selected by a 10 combination of two impulses, one of the branch circuits being selected and locked by the first impulse of the combination, a relay in the other branch of the selecting circuit selected and operated by the second 15 impulse of the combination of impulses, a clearing-out relay having an operating circuit closed at the armature of the relay in the second branch and operating at the cessation of the second impulse to return the 20 selecting circuit to normal condition.
4. In a printing telegraph the combination with a carriage movable forward step-by-step, of means to return said carriage to normal position from any part of its stroke, 25 comprising a relay, a selecting circuit for said relay energized by a combination of impulses, a circuit closed by the energization of said relay, said circuit including a reset magnet, and releasing means operated by 30 the armature of said reset magnet to allow said carriage to return to normal.
5. In a printing telegraph the combination of a movable paper carriage, means for moving said carriage forward step-by-step, 35 as each character is printed, a motor for returning said carriage to normal position, electro-magnetic means for starting said motor, an energizing circuit for said electro-magnetic means, and means for closing said 40 energizing circuit selectively operated by a combination of two impulses.
6. In a printing telegraph the combination of a rotatable type shaft carrying a type wheel having two rows of characters thereon, means for moving said type wheel longitudinally of the shaft for bringing either of said rows of characters into printing position, said means including an electromagnet having an energizing winding 50 and a holding winding, means for affecting said energizing winding, means for energizing said holding winding, and a relay selectively energized by a combination of impulses to deenergize said holding winding whereby the type wheel is returned to normal position.
7. In a printing telegraph system the combination of a plurality of type magnets, each having two energizing windings, said 55 windings being arranged in groups; a selecting circuit comprising a plurality of branches and operated in response to a combination of two impulses; and a selecting apparatus comprising means energized but not locked on the first impulse, means controlled thereby for closing a branch of said selecting circuit through one of the windings of a group of type magnets, and means operated and locked by the second impulse of the combination of impulses for 70 closing and locking a second branch of said selecting circuit through a second group of type magnets.
8. In a printing telegraph system, the combination of a rotatable type shaft carrying a plurality of characters thereon, means for selectively stopping said shaft to bring any of said characters into printing position, said means comprising a selecting circuit selectively energized in response to a 75 combination of two impulses, a relay in said selecting circuit, a circuit controlled by said relay and including means for starting the rotation of the type shaft, and a clearing-out relay operating after the printing operation 80 to return the selecting circuit to normal.
9. In a printing telegraph system, the combination of a selecting circuit, a relay in said circuit selectively operated by a combination of two impulses, a type shaft carrying a type wheel having two rows of characters thereon, shifting means for moving said type wheel longitudinally of the shaft, an energizing circuit for said shifting means closed by the selected relay in the selecting 90 circuit, and means included in the energizing circuit of the shifting means for locking the same in energized condition.
10. In a printing telegraph system, the combination of a selecting circuit having two relays therein and selectively operated by the same combination of impulses, a rotatable type shaft carrying a type wheel having two rows of characters thereon and movable longitudinally of the shaft, a shift 100 magnet having an energizing circuit closed and locked by one of the relays in the selecting circuit whereby the type wheel is moved longitudinally of the shaft, and means operated by the closure of the energizing circuit for the shift magnet to prevent the 105 operation of the other relay in the selecting circuit.
11. In a printing telegraph system, the combination of a selecting circuit having two relays therein and selectively operated by the same combination of impulses, a rotatable type shaft carrying a type wheel having two rows of characters thereon and movable longitudinally of the shaft, a shift 110 magnet having an energizing circuit closed and locked by one of the relays in the selecting circuit whereby the type wheel is moved longitudinally of the shaft, and means operated by the closure of the energizing circuit for the shift magnet whereby the operation 115 of the other relay in the selecting circuit is prevented.
12. In a printing telegraph system, a 120 paper carriage movable forward step by

- step to print successive characters, in combination with means for resetting the paper carriage from any point in its stroke, and for moving the paper across the face of the carriage to provide a clean surface for a succeeding line of characters, said means comprising a selecting circuit having two relays therein simultaneously selectively energized by a combination of two impulses, means operated by one of said relays to allow said carriage to return to its normal position, a paper lift magnet, an energizing circuit therefor having break point therein closed jointly by the other magnet in the selecting circuit and by the return of the carriage to its initial position whereby the paper is moved across the face of the paper carriage.
13. In a printing telegraph system the combination of a plurality of type magnets, each having two windings and selectively energized by a combination of two impulses; a selecting circuit for said type magnets composed of a plurality of branches; select-

ing apparatus comprising means energized but not locked on the first impulse, means controlled thereby for closing and locking one of the branches of said selecting circuit, and means energized and locked by the second impulse of a combination for closing a second branch of said selecting circuit, one of said magnets being common to one winding in each of the closed branches of said selecting circuit, whereby a character is selected; means for recording the character selected; and means operated at the completion of the recording operation to allow said selecting circuit to return to normal.

In witness whereof, we hereunto subscribe our names this 13th day of February A. D., 1912.
